UNITED STATES PATENT OFFICE.

WILLIAM SCHWERING, OF PHILADELPHIA, PENNSYLVANIA.

GAS-STOVE-VALVE-LOCKING DEVICE.

No. 893,662.

Specification of Letters Patent. Patented July 21, 1908.

Application filed November 21, 1907. Serial No. 403,129.

To all whom it may concern:

Be it known that I, WILLIAM SCHWERING, a citizen of the United States, residing at Philadelphia, in the county of Philadelphia, 5 and State of Pennsylvania, have invented certain new and useful Improvements in Gas-Stove-Valve-Locking Devices, of which the following is a specification.

This invention relates to a gas stove valve locking device, the object being to provide a locking device which can be readily attached to an ordinary stove now in use whereby all liability of the valve being turned accidentally is prevented.

15 Another object of my invention is to provide a locking device which is adapted to be placed adjacent to each valve on the gas stove so that each valve can be opened and closed independently of each other.

20 A further object of my invention is to provide very novel means for locking the locking member, which is adapted to engage the handle of the valve, whereby all danger of the locking member being moved is prevented.

25 A further object is to provide a device which is exceedingly cheap in construction and one which can be attached to a gas stove in a very few minutes.

These objects are obtained by the novel 30 arrangement and construction of parts hereinafter fully described and shown in the accompanying drawings in which:—

Figure 1, is a front view of a portion of a gas stove, showing the application of my improved locking device. Fig. 2, is a top plan view of the same. Fig. 3, is a section taken on line 3—3 of Fig. 1. Fig. 4, is an end view of one of the locking devices detached, and Fig. 5, is a section taken on line 5—5 of Fig. 1.

40 Referring to the drawings A, indicates a portion of the top of an ordinary gas stove which is provided with a flange A', through which the feed pipes B, leading to the burner are adapted to extend, the ends of the feed pipes B, being connected with a supply pipe C, all of which are the ordinary construction now in use.

Each of the feed pipes B, are provided with 50 a valve casing in which is mounted a turning plug D, carrying a handle D', for opening and closing the valves.

55 Openings are formed in the depending flange A', to one side of the feed pipes and in a plane above the same through which is adapted to extend a threaded bolt E', of the

member E, forming the fixed member of my improved locking device, the bolt being secured therein by nut E'', it of course, being understood that the openings can be formed 60 in the flanged part of the top when the stove is being made if desired.

The member E, is provided with an ear E', over which is pivotally mounted the space ears F', of the pivoted locking member F, the 65 members being secured together by a rivet F'.

The pivoted member F, is provided with a depending arm G, at its lower end which is flanged outwardly, as shown at G', so it will not engage the plug of the valve when turned 70 down along side of the handle D, as shown, which will lock the plug in a closed position whereby it will be impossible to move the same without raising the member F. It will also be seen that when the pivoted member 75 is thrown down after the valve has been opened, the valve will be locked in that position.

Pivots mounted on the member F, is an auxiliary locking clip H, which is bowed as 80 shown at H', and is provided with a pin H'', whereby it can be readily swung on its pivot and it will be seen that when swung into position, as shown in Fig. 3, the pivoted member will be securely locked so that it cannot 85 be raised.

The locking clip is provided with a lug H', which is adapted to engage one side of the member E, to prevent the clip from swinging too far around so that it will be held over the 90 fixed and pivoted member whereby the pivoted member will be prevented from being moved upwardly.

From the foregoing description it will be seen that I have provided a locking device 95 for each valve, each one of which can be operated independently so that any one of the valves can be locked, closed or opened by simply throwing the clip to one side and swinging the arm upwardly so as to allow the 100 handle to be turned, whereby the valve can be locked in any position desired.

Having thus described my invention, what I claim as new and desire to secure by Letters Patent is:

1. The combination with a gas stove provided with valves, of fixed members, a member pivoted to said fixed members provided with arms for locking said valves and means for locking said pivoted members.

2. The combination with a gas stove provided with valves, of a member secured to

said stove, a member pivoted to said member provided with a depending arm adapted to be normally held in engagement with the handle of one of said valves and means for locking said pivoted member.

3. The combination with a gas stove provided with valves, of locking members pivotally connected to said stove adapted to lock said valves, closed or opened, and means for locking said locking members, for the purpose described.

4. The combination with a gas stove provided with a plurality of feed pipes having valves arranged therein, of members detachably secured to the top of the stove, members pivotally mounted on the first mentioned members, said pivoted member being provided with depending arms and clips pivotally mounted on the pivoted members for locking said pivoted member, for the purpose described.

5. The combination with a gas stove provided with feed pipes carrying valves, of members fixed to the top of the stove adjacent each valve, said members being provided with ears, members provided with space ears pivotally mounted on the ears of the fixed members by rivets, said pivoted members being provided with depending arms and clips pivotally mounted on the pivoted members, provided with lugs adapted to engage said fixed members whereby said pivoted members will be locked when said clips are thrown into alignment with said members. 25 30 35

In testimony whereof I have signed my name to this specification in the presence of two subscribing witnesses.

WILLIAM SCHWERING.
